CAN CONSTRUCTION

Benjamin F. Goodwin, Ridgewood, N. J., assignor
of one-half to Seeman Brothers, Inc., a cor-
poration of New York

Application June 25, 1932, Serial No. 619,262

12 Claims. (Cl. 220—72)

This invention relates to new and useful improvements in the construction of cans and broadly speaking refers to any type of can. In a preferred application of the invention it has especially reference to cans containing food products.

In the ordinary construction of cans to contain any material the top and bottom walls are generally rather flexible and this flexibility in many instances is objectionable and the invention herein is designed to particularly stiffen the top and bottom walls of the can for the purposes and reasons hereinafter mentioned.

Heretofore in the construction of cans for the reception of food products and to be sold as canned goods, these cans have preferably, on the top and bottom walls, been provided with strengthening ribs or corrugations forming a series of elevations or depressions arranged in lines parallel to each other and to the peripheral edge of the can. In other words, in a circular top can the strengthening ribs or corrugations would be disposed in a circular manner. In a can such as a sardine can, generally oval in shape, the strengthening ribs or corrugations would be disposed in an oval manner parallel to each other and to the outer edge of the can. In the case of a can having a substantially rectangular outline the strengthening ribs or corrugations would be disposed parallel to each other and to the edge of the can and, therefore, would be substantially rectangular in shape. It is, of course, well known that can goods, especially food products, under certain detrimental conditions, may deteriorate and cause the formation of gas which will create

a pressure within the can and will cause a bulging of the top or the bottom wall known as "springing". When this occurs, either merchants, Government inspectors, or consumers who are aware of the significance of this "springing" will reject such a product. It has been discovered that with cans constructed in the ordinary manner with the above well known types of reinforcement ribs or corrugations that "springing" of either the top or bottom wall or both may easily occur although the food product within the can is in perfect condition. Among other things this particular form of "springing" has been found to be due to the fact that the top and bottom walls, even with the usual reinforcement are too flexible and when the top of the can is crimped on by machinery undue tension or pressure is exerted on the can which causes either one or both of these walls to bulge slightly or assume a curved position. This action in effect, therefore, would cause and has caused the "springing" or bulging making an ap-

pearance which seems to indicate to the observer that the contents of the can are not in good condition and has caused the rejection of a measurable percentage of cans without any real reason for this rejection on the grounds of inferior quality of the food product within the can. It is further to be clearly understood that my invention has been, and can be, applied to cans of any sort, either containing food products or any other products, whether or not the cans are provided with the usual peripheral corrugations above mentioned. My invention can be applied to cans the top and bottom walls of which are otherwise perfectly smooth.

It is the object of this invention to avoid this unjustified and abnormal "springing" which is due in some cases to the strain put on the can by crimping the cover thereon.

Further and more specific objects, features and advantages will more clearly appear from a consideration of the specification hereinafter taken in connection with the accompanying drawing which forms part of the specification and which illustrates a present preferred form of the invention.

In broad general terms the application comprises the provision to the bottom and/or top of any kind of can of transverse, preferably arcuate or curved, ribs, grooves, or corrugations disposed preferably transverse to the diameter or major axis of the surface to stiffen the same, and in the broad sense without regard to whether or not the can has other reinforcement elements disposed on or formed therein.

To further achieve this object of the invention on certain types of food containers, the invention hereinafter described in detail, broadly includes the provision of the top or bottom or both of the can walls with intersecting ribs, corrugations, or grooves so that at least some of these reinforcing elements are disposed in a direction non-parallel to the periphery of the can and intersecting the ordinary and usual reinforcing ribs or elements as above described. As a general example of this, an oval sardine can provided with the usual oval ribs, corrugations, or depressions parallel to the periphery and to each other is provided with a plurality of depression ribs or corrugations disposed in a direction to intersect the usual reinforcing ribs or depressions and may be either straight-line, curved or irregular, but preferably they are arcuate in shape especially where the normal reinforcing corrugations are curved and are generally disposed in a direction substantially at

right angles to the normal elements which they intersect.

It is, of course, to be understood that when I refer to a container for food I mean a closed container either the usual metal can or a jar of glass or other material having a flexible cover. It is apparent that even a glass jar with a metal cover or top containing food might well employ this invention for the cover or top might be 10 caused to bulge unnecessarily by strains in the manner previously described. Therefore, be it understood that the use of the word "container" in this application covers any container such as a can or jar as long as one wall is of flexible 15 metal which may be strained in the manner above specified.

The preferred form of the invention is shown in the drawing, of which:

Fig. 1 shows the usual type of can assumedly 20 containing food products in perfect condition and yet preferably because of the crimping of the cover having a curvature in the top and bottom walls which would seemingly indicate deterioration of the contents;

Fig. 2 is a cross-section through the can which 25 has been provided in accordance with my invention;

Fig. 3 is a plan view of the can structure in accordance with this invention.

The can shown in the drawing is a preferred 30 form but is merely illustrative of the idea since the invention may be applied to cans of any shape or cross-section. In the drawing, a can 10 is provided with a top wall 11 and a bottom wall 35 12 having the usual series of peripheral ribs, grooves, or corrugations, 13 and 14. In the usual construction of the can there may be two or more of these ribs, but it will be noted that they are disposed in a spaced relation on the respective 40 surfaces with regard to each other and are preferably parallel to each other and to the edge or outline of the can. These reinforcing elements are generally formed by die action in the manufacture of the can.

Referring to Fig. 1 it will be seen that these 45 top and bottom walls are shown as curved. This curvature is shown to represent the effect which is produced on ordinary cans in a great many cases where the cover is mechanically crimped onto the can and is caused by the strain put on the can by the crimping action. If cans of this 50 type were sold on the market with high grade food products therein it might be, and are in many cases, rejected because of the "springing" 55 or bulging without any deterioration having taken place in the products therewithin. Referring to Figs. 2 and 3 it will be noted that in addition to the well known ordinary reinforcing elements there have been provided the auxiliary reinforcing elements 15 and 16 which as shown 60 have been placed on the can in the form of grooves 15 and 16 disposed in a direction to intersect or cross one or more of the ordinary reinforcing elements. In other words, the top and bottom of 65 the can constructed in accordance with my invention has now been provided not only with parallel spaced grooves but with a plurality of intersecting grooves, ribs, or corrugations in the form of can shown in the drawing. The additional reinforcing elements are preferably arcuate in shape, since the ordinary reinforcing elements are curved and they are disposed in a 70 manner and direction transverse to the direction of the ordinary reinforcing ribs. It is to be understood, however, that they may be straight-

line, arcuate, or curved, or may be disposed in a zig-zag fashion depending upon the necessities and requirements of each case. It will be noted that these intersecting, preferably transverse, reinforcing elements extend substantially across the can to intersect the normal reinforcements but they do not extend beyond or cross the outer corrugations or rib which is disposed next adjacent the edge of the can. 80

In the preferred form of can, therefore, the auxiliary or intersecting reinforcing elements extend across the can top or bottom up to the outer reinforcement but do not intersect or cross it. 85

This invention, therefore, it will be seen provides additional reinforcements in the nature of transverse or intersecting reinforcements which it has been found prevent the abnormal and unnatural "springing" or bulging due to mechanical crimping so that cans containing high grade food 90 therein will not bulge, although it will not prevent bulging if for any reason the food within the can becomes deteriorated and gas pressure is created. By this simple and efficient means, therefore, the rejection of cans containing high grade food due to seaming and unnatural "springing" is prevented and a considerable waste of perfectly good products is avoided. 95

It is to be carefully noted that the transverse grooves or corrugations 15 and 16 can and are intended to be applied as well to the tops and bottoms of cans in the same manner as herein indicated even when the cans have no other corrugations or grooves thereon. It has been found that corrugations of this general type produce a desired stiffening action whether or not other reinforcing elements are disposed on or formed in the can wall. 100

While the invention has been described in detail and with respect to a present preferred form thereof it is not to be limited to such details 115 and forms since many changes and modifications may be made in the invention without departing from the spirit and scope of the invention in its broadest aspects. Hence it is desired to cover any and all forms and modifications of the invention 120 which may come within the language or scope of any one or more of the appended claims.

What is claimed, is:

1. A construction of container for food products which comprises a wall member having a plurality of spaced curved, corrugations therein disposed parallel to the periphery of the can, and additional curved corrugations disposed in an arcuate fashion substantially transverse to and intersecting the first mentioned corrugations. 125

2. A construction of container for food products which includes top and bottom wall members having an oval outline, a plurality of spaced parallel reinforcing ribs or grooves formed in each wall member parallel to the peripheral edge 135 of the can, and an auxiliary reinforcing rib or groove formed in the wall member in a curve substantially intersecting the other reinforcing elements at right angles. 130

3. A construction of container for food products which includes top and bottom wall members having an oval outline, a plurality of spaced parallel reinforcing ribs or grooves formed in each wall member parallel to the peripheral edge of the can, and an auxiliary reinforcing rib or groove formed in the wall member in a curve 140 substantially intersecting the other reinforcing elements at right angles, said auxiliary reinforcing element terminating just short of the outer reinforcing rib or groove. 145

4. In combination, a sealed, substantially airtight can made of relatively thin metal and used for food products which comprises a wall member having a plurality of spaced corrugations therein disposed parallel to the periphery of the can, and a continuous auxiliary strengthening corrugation disposed on the wall member to extend across said first named corrugation. 80
5. In combination, a sealed, substantially airtight can made of relatively thin metal and used for foods products which includes top and bottom wall members having a predetermined outline, a plurality of spaced reinforcing ribs or grooves formed in each wall member parallel to the periphery of the can, and an auxiliary reinforcing rib or groove formed in the wall members in a direction substantially transverse to and crossing at least one of the first mentioned corrugations. 85
- 10 6. In combination, a sealed, substantially airtight can made of relatively thin metal and used for food products which includes top and bottom wall members having a predetermined outline, a plurality of spaced reinforcing ribs or grooves formed in each wall member parallel to the periphery edge of the can, and an auxiliary reinforcing rib or groove formed in the wall members in a direction substantially transverse to and crossing at least one of the other reinforcing elements at right angles. 90
- 15 7. In combination, a sealed, substantially airtight can made of relatively thin metal which comprises a wall member having a strengthening corrugation therein disposed parallel to the periphery of the can, and a continuous auxiliary strengthening corrugation disposed on the wall member and extending from one to another portion of the first named corrugation. 95
- 20 8. In combination, a sealed, substantially airtight can made of relatively thin metal which comprises a wall member having a strengthening corrugation therein disposed parallel to the periphery edge of the can, and an auxiliary reinforcing rib or groove formed in the wall members in a direction substantially transverse to and crossing at least one of the other reinforcing elements at right angles, said auxiliary reinforcing element terminating just short of the outer reinforcing rib or groove. 100
- 25 9. In combination, a sealed, substantially airtight can made of relatively thin metal which includes top and bottom wall members having a predetermined outline, a reinforcing rib or groove formed in each wall member parallel to the periphery edge of the can, and a continuous auxiliary reinforcing rib or groove formed in the wall members and extending from one to another portion of the first named rib at substantially right angles. 105
- 30 10. In combination, a sealed, substantially airtight can made of relatively thin metal which includes top and bottom wall members having a predetermined outline, a reinforcing rib or groove formed in each wall member parallel to the periphery edge of the can, and a continuous auxiliary reinforcing rib or groove formed in the wall members and extending across the first named rib. 110
- 35 11. In combination, a sealed, substantially airtight can made of relatively thin metal and used for food products which comprises a wall member having a plurality of spaced curved, corrugations therein disposed parallel to the periphery of the can, and additional curved corrugations disposed in an arcuate fashion substantially transverse to and intersecting the first mentioned corrugations. 115
- 40 12. In combination, a sealed, substantially airtight can made of relatively thin metal and used for foods which comprises top and bottom wall members having an oval outline, a plurality of spaced parallel reinforcing ribs or grooves formed in each wall member parallel to the peripheral edge of the can, and an auxiliary reinforcing rib or groove formed in the wall member in a curve substantially intersecting the other reinforcing elements at right angles. 120
